UNITED STATES PATENT OFFICE.

ALFRED SPINK, OF DAVENPORT, IOWA.

PRESS.

1,109,710.

Specification of Letters Patent.

Patented Sept. 8, 1914.

Application filed November 19, 1913. Serial No. 801,865.

To all whom it may concern:

Be it known that I, ALFRED SPINK, a citizen of the United States, residing at Davenport, in the county of Scott and State of Iowa, have invented certain new and useful Improvements in Presses, of which the following is a specification.

My invention relates to improvements in presses, such as are adapted to be preferably manually operated, for pressing paper or 10 the like into suitable bales.

An important object of this invention is to provide a press of the above mentioned character, which is simple in construction, 15 convenient in use, and quick and reliable in operation.

A further object of the invention is to provide a press of the above mentioned character, which is so constructed that the same 20 may be quickly and easily filled with the material to be pressed, and the completed bale removed from the press, in a similar manner.

A further object of this invention is to 25 provide novel means to detachably lock the side or door of the baling chamber or casing in its closed position, such means being automatically operated to hold the door in its closed position upon being moved to such 30 closed position, and adapted to be readily manually operated to release the door.

A further object of the invention is to 35 provide a press of the above mentioned character, so constructed that the pressing element or follower will automatically gravitate to its starting position, upon the release of the operating shaft.

Other objects and advantages of this invention will be apparent during the course 40 of the following description.

In the accompanying drawings forming a part of this specification and in which like numerals are employed to designate like parts throughout the same, Figure 1 is an 45 elevation of the front longitudinal side of a hay press embodying my invention, Fig. 2 is an elevation of the transverse side of the same, Fig. 3 is a plan view of the same, Fig. 4 is a horizontal section taken on line 4—4 of Fig. 1, Fig. 5 is an elevation of the front 50 longitudinal side of the press, with the side or door removed, Fig. 6 is a longitudinal sectional view taken on line 6—6 of Fig. 1, Fig. 7 is a perspective view of the lower 55 pressing member or follower, and, Fig. 8 is a side elevation of the means for turning the

operating shaft, a part of such means being removed.

In the drawings, wherein for the purpose of illustration is shown a preferred embodiment of my invention, the numeral 10 designates a preferably vertical pressing or baling chamber or casing, having its rear longitudinal side closed by a longitudinal side piece 11, which is permanently connected with transverse side pieces 12 forming a chamber or casing having its forward longitudinal side 13 open, as shown. The transverse sides 12 diverge slightly forwardly, as shown in Fig. 4, whereby the forward open side 13 is larger than the opposite closed side, thus enabling the bale to be quickly and easily removed, as will be explained. The lower end of the baling chamber or casing 10 is closed by a stationary bottom 14, which is rigidly connected with the lower portions of the longitudinal and transverse side pieces 11 and 12. Connected with the bottom 14 are longitudinal beams or strips 15, which are mounted upon transverse beams 80 or strips 15', as shown. The open longitudinal side 13 is normally closed by a removable door or side 16, which is provided near its lower end with a transverse strip 17, rigidly connected therewith and extending beyond the same at both ends, to engage with the forward longitudinal edges of the transverse side pieces 12. The transverse strip 17 is arranged upon the exterior surface of the door 16, whereby the door passes inwardly 90 between the transverse side pieces 12 and inwardly of a holding strip 18, rigidly connected with the transverse side pieces 12. It is thus seen that the strips 17 and 18 serve as means to hold the lower end of the door 16 in its operative position, when moved thereto, and allow of the removal of the door when desired. Connected with the upper end of the removable door 16 is an upper transverse strip 19, extending at both ends 100 beyond the door 16 and adapted to engage with swinging holding dogs 20, pivoted upon the transverse side pieces 12, as shown at 21. The dogs have their inner ends provided with heavy weights 22, to swing the hooked ends thereof upwardly.

The numeral 23 designates fixed stops, disposed to engage with the weights 22, to positively limit their downward movement.

The hooked ends of the holding dogs 20 have their outer ends 24 so shaped or beveled that the same will be automatically forced

downwardly when engaged by the transverse strip 19, whereby the holding dogs will automatically grip the strip 19. It is obvious that the holding dogs may be readily swung to release the strip 19 when desired.

Connected with the removable door 16 near and spaced from the upper transverse strip 19 are suitably stiff approximately L-shaped spring clamps 25, adapted to engage the exterior surfaces of the transverse side pieces 12, serving to connect them with the door 16 and prevent such end pieces from bulging. It is obvious that the clamps 25 also serve as guide means, when the door 16 is being moved to its closed position, such clamps however not interfering with the movement of the door, when the same is being placed in or removed from its operative position.

20 The numeral 26 designates a top piece or head, closing the upper end of the baling casing or chamber 10. This top piece is hinged with the rear side piece 11 and reinforcing strips 11', as shown at 27, to be 25 swung in a substantial vertical plane. The free edge of the top piece 26 is disposed adjacent and inwardly of the upper end of the door 16, and is partially overlapped by said door, the top piece 26 swinging downwardly 30 to assume a position between and below the upper ends of the longitudinal and transverse side pieces 11 and 12. Rigidly mounted upon the upper surface of the top piece 26 is a lug 28 adapted to engage the upper 35 end of the rear side piece 11 and reinforcing strip 11', when the top piece 26 is swung to its open or upper position, to support the latter in such position.

40 The top piece 26 preferably includes transverse reinforcing strips 29, upon which are rigidly mounted bearings 30, through which is journaled a longitudinal operating shaft 31, as shown. The operating shaft 31 extends outwardly at both ends beyond the 45 bearings 30 and the end pieces 12 and has spools 32 and 33 rigidly connected therewith. Connected with these spools by means of eye-bolts 34 or the like, are depending flexible elements, preferably chains 35, the 50 lower ends of which are attached to U-bolts 36, carried by the free ends of a longitudinal bar 37. This bar 37 operates through longitudinal slots 38 formed in the transverse side pieces 12 and has a pressing member or follower 39 connected therewith, as 55 more clearly shown in Fig. 7. This follower is slightly tapered to properly fit within the baling chamber. It is thus seen that by rotating the operating shaft 31 the chains 35 will be wound upon the spools 32 and 33 whereby the follower 39 will be elevated or moved toward the coacting top piece or 60 pressing member 26. The follower or pressing member 39 is provided with transverse 65 grooves 39', which are in registration with

longitudinal grooves 40', formed through the rear side piece 11, the upper end of the grooves 40' being in registration with grooves 41' formed through the member 26. The tying wires are passed around the bale 70 by being passed through the grooves 39', 40' and 41'.

75 The spool 33 has a ratchet wheel 40 rigidly connected therewith, the same being preferably cast integral with the spool. This ratchet wheel is engaged and turned by a pawl 41, pivotally mounted within an operating head 42, comprising side plates 43, which are apertured to rotatably receive the outer end of the spool 33. The side 80 plates 43 are connected by transverse bolts 44 and the pawl 41 is pivotally connected therewith by a transverse bolt 45. At its outer end the operating head 42 is provided with a socket 46, having an operating lever 47 clamped therein. It is obvious that by swinging the lever 46 up and down, the pawl 41 will intermittently rotate the shaft 31 in one direction, that is to wind the chains 35 upon the spools.

90 Rigidly mounted upon the operating shaft 31 at the central portion thereof, is a holding ratchet wheel 48, (see more particularly Fig. 6), adapted to be engaged by a coacting tooth or pawl 49, formed upon a curved hand operated lever 50, pivotally connected with the lug 28, as shown. The curved lever automatically retains the tooth in engagement with the ratchet wheel. The teeth of the holding ratchet wheel 48 are so faced that when they are engaged by the tooth or pawl 49, the shaft 31 is prevented from rotating in the direction to allow the chains 35 being unwound from the spools 32 and 33, but not interfering with the rotation of the shaft 31 in a reverse direction. It is 105 obvious that by swinging the hand lever 50 in the proper direction, the tooth 49 will be moved out of engagement with the ratchet wheel 48 to release the shaft 31.

110 The operation of the apparatus is as follows: To fill the baling chamber with material to be compressed, the door 16 is arranged in its operative position, to close the open side 13 of the main casing. The top piece 115 or pressing member 26 is now swung upwardly to assume the outer position, whereby the upper end of the casing or chamber 10 is entirely open to receive material to be compressed. The casing 10 having been 120 suitably filled with the material to be compressed, the end piece or pressing element 26 is swung downwardly to assume its inner or closed position. The operator swings the lever 47 up and down, to rotate the shaft 31, 125 whereby the chains 35 are wound upon the spools 32 and 33. This causes the follower or pressing member 39 to move upwardly toward the top piece or pressing element 26, whereby the material is caught between the 130

same and suitably compressed. After the desired pressure has been placed upon the material which is now in the form of a bale, the door 16 may be removed, whereby the 5 tying wires may be run around the bale, as is well known. The tooth 49 is now holding the shaft 31 against rotation, whereby to remove the bale, the lever 50 is swung away from the ratchet wheel 48, so that the follower or pressing member 39 will be free to 10 gravitate to its lower position. The top piece 26 will now be swung to the open position, if desired. The bale is easily removed from the casing 10 through the open 15 side 13 thereof, it being remembered that this side of the casing 10 is slightly wider than the closed side 11.

It is to be understood that the form of my invention herewith shown and described is 20 to be taken as a preferred example of the same, and that various changes in the shape, size and arrangement of parts may be resorted to without departing from the spirit of the invention or the scope of the sub- 25 joined claims.

Having described my invention, I claim:—

1. In a press of the character described, a baling chamber having its side walls diverging toward the open side of the baling chamber, a movable door to normally close the open side of the baling chamber and adapted to be moved to open and closed positions, a movable head mounted upon the upper end of the baling chamber near one 35 end thereof and adapted to be moved to open and closed positions, a follower mounted within the baling chamber to move longitudinally thereof, an operating shaft mounted upon the head, and connecting means be- 40 tween the operating shaft and the follower.

2. In a press of the character described, a baling chamber having one longitudinal side piece and the transverse side pieces permanently connected and the transverse side 45 pieces diverging toward the open side of the baling chamber, a removable door to close the open side of the baling chamber, a head hinged to the baling chamber to close one end thereof and adapted to be swung to an 50 open position, a follower mounted within the baling chamber to move longitudinally thereof, an operating shaft mounted upon the head, and flexible elements arranged upon opposite sides of the baling chamber 55 and connected with the operating shaft and follower.

3. In a press of the character described, an upstanding baling chamber having its upper end open, a movable head to normally 60 close the upper end of the baling chamber and adapted to be moved to an open position whereby the baling chamber may be conveniently filled with the material to be pressed, a follower mounted within the baling chamber and movable upwardly toward 65

the head for compressing the material, and means connecting the follower and head and adapted to be operated to effect the upward movement of the follower.

4. In a press of the character described, 70 an upstanding baling chamber including a plurality of walls, the oppositely arranged walls diverging toward the open side of the baling chamber, a holding strip attached to the lower end of the baling chamber upon the open side thereof, a removable door 75 adapted for insertion within the open side of the baling chamber to have its lower end arranged inwardly of and in engagement with the holding strip, a locking strip connected with the removable door near the upper end thereof, holding dogs pivoted to the opposite diverging walls and adapted to engage with the locking strip and having their ends provided with weights whereby the free ends 80 thereof will automatically swing upwardly, fixed stops arranged below the weights to positively limit their downward movement, and means arranged within the baling chamber to press the material therein. 85

5. In a press of the character described, 90 the combination with an upstanding baling chamber, of a head hinged to the upper end thereof and adapted to be swung to open and closed positions, an operating shaft 95 mounted upon the head, a follower movably mounted within the baling chamber, flexible elements arranged upon opposite sides of the baling chamber and connected with the operating shaft and follower, means to rotate the operating shaft in one direction, and means normally serving to prevent the rotation of the shaft in a reverse direction. 100

6. In a press of the character described, 105 the combination with an upstanding baling chamber, of a head hinged to the upper end thereof and adapted to be swung to open and closed positions, an operating shaft mounted upon the head and extending longitudinally thereof, a follower movably 110 mounted within the baling chamber, flexible elements arranged upon opposite sides of the baling chamber and connected with the operating shaft and follower, means to rotate the operating shaft, a ratchet wheel connected with the operating shaft between the ends thereof, and a holding pawl pivotally connected with the head and adapted to engage the ratchet wheel to prevent the rotation of the operating shaft in one direction. 115

7. In a press of the character described, 120 the combination with an upstanding baling chamber, of a head hinged to the upper end thereof and adapted to be swung to open and closed positions, an operating shaft 125 mounted upon the head, a follower movably mounted within the baling chamber, flexible elements connecting the operating shaft and follower, means to rotate the operating shaft, 130

4
a ratchet wheel connected with the operating shaft between the ends thereof, and a curved lever pivoted to the head adjacent the ratchet wheel, overhanging said ratchet wheel, and provided with a tooth to engage said ratchet wheel.

8. In a press of the character described, the combination with an upstanding baling chamber, of a movable head connected with the upper end thereof and adapted to be moved to open and closed positions, a follower mounted within the baling chamber, an operating shaft mounted upon the head, flexible elements connecting the follower and operating shaft, pawl and ratchet means to rotate the operating shaft in one direction, and pawl and ratchet means to normally hold the shaft against movement in an opposite direction.
9. In a press of the character described, an upstanding baling chamber having its upper end and one side formed open, a movable door to normally close the open side of the baling chamber, a movable head to normally close the upper end of the baling chamber, a follower mounted within the baling chamber and movable upwardly toward the head for compressing material within the baling chamber, a rotatable element mounted upon the head, and connecting means between the rotatable element and follower, substantially as described.
10. In a press of the character described, the combination with an upstanding baling

chamber, of a head hinged to the upper end thereof and adapted to be moved to open and closed positions, an operating shaft mounted upon the head, a lug mounted upon the operating shaft to engage a wall of the baling chamber when the head is swung to its open position to support the same, a ratchet wheel connected with the operating shaft, a pawl pivotally connected with the lug and arranged to engage with the ratchet wheel, means to rotate the operating shaft, and pressing mechanism operated by said shaft.

11. In a press of the character described, the combination with an upstanding baling chamber, having opposite side walls provided with longitudinal slots and one side formed open, of a movable door to normally close the open side, a movable head to normally close the upper end of the baling chamber, an operating shaft mounted upon the head, a follower mounted within the baling chamber, a bar connected with the follower and operating within the longitudinal slots and extending therebeyond, flexible elements connecting the bar and operating shaft, and means to rotate the operating shaft.

In testimony whereof I affix my signature in presence of two witnesses.

ALFRED SPINK.
